The ornamental design for a combined container and lid, as shown and described.

DESCRIPTION

FIG. 1 is a top, front perspective view of a combined container and lid, showing my new design;

FIG. 2 is a top view thereof;

FIG. 3 is a bottom view thereof;

FIG. 4 is a front view thereof, the rear view being a mirror image thereof;

FIG. 5 is a side view thereof, the opposite side view being a mirror image thereof;

FIG. 6 is a bottom front perspective view thereof;

FIG. 7 is an exploded top, front perspective view thereof;

FIG. 8 is an exploded front, bottom perspective view thereof; and,

FIG. 9 is a cross-sectional view thereof, taken along line 9-9 of FIG. 1.
